ABSTRACT OF THE DISCLOSURE

The rate of descent of a wireline tool in a wellbore containing a column of heavy oil is increased by coating the tool with a surface active agent capable of promoting the formation of a film of water on the tool and thereby after lowering the tool in the wellbore.

BACKGROUND OF THE INVENTION

Field of the invention

This invention relates to well operations and is particularly concerned with wireline operations carried out in wells producing heavy crude oil.

Description of the prior art

Many oil field operations require the lowering of wireline tools into wells through crude oil in the tubing or casing. Typical operations of this kind include the making of bottom-hole pressure measurements and temperature surveys, the setting and releasing of packers and bridge plugs, the setting and retrieving of gas lift valves, the running of logging tools of various types, the swabbing of wells, and the like. Although such operations can often be carried out routinely, there are certain wells in which the lowering of wireline tools presents serious problems. The rate of descent of such a tool depends in part on the weight of the tool and the density and viscosity of the fluids present in the wellbore. In wells containing low gravity crude oils, this rate may be so low that conventional wireline operations are not feasible. The difficulties thus encountered can be alleviated in some cases by using heavy sinker bars to increase the rate of descent but this is often impractical because the length of the lubricator precludes the use of bars of sufficient weight. It may therefore be necessary to kill the well and pull the tubing string or displace the heavy oil with a lighter fluid through which the wireline tool can be lowered. This is costly and time consuming and hence is avoided wherever possible, often at the expense of needed tests or well improvements.

SUMMARY OF THE INVENTION

This invention provides an improved method for the lowering of wireline tools into wells containing low gravity crude oils and similar fluids. In accordance with the invention, it has now been found that the rate of descent of such tools can be improved significantly by coating the tools with surface active agents before they are lowered through the oil. Although the phenomena responsible for the improved results obtained are not fully understood, it appears that the presence of the surface active agent results in the formation of a film which serves to lubricate the tools through the heavy oil. Most low gravity crude oils and similar fluids contain some dispersed water, even though the amount present may be quite small. The addition of a surface active agent which tends to make the surface of a wireline tool water-wet and at the same time promotes the separation of dispersed water from the oil apparently results in the formation of a thin film of water on the tool surface. This film re-

2

duces the friction between the tool and oil and thus produces an increase in the rate in which the tool descends through the heavy oil column. Other phenomena may also be involved. Regardless of the mechanism involved, tests have shown that the invention facilitates the carrying out of wireline operations and often permits such operations in wells where they would not otherwise be feasible. The savings thus made possible are often substantial.

10 DESCRIPTION OF THE PREFERRED EMBODIMENTS

The method of the invention involves the coating of a wireline tool to be lowered into a wellbore containing a heavy crude oil or similar fluid with a surface active agent. This can be done by painting, spraying, dipping or smearing the tool with the surfactant before it is introduced into the well. An alternate procedure involves pouring the surfactant into the lubricator and lowering the tool into it. In either case, it is preferable that the surface of the tool be clean and substantially free of oil before the surfactant is applied. Alcohol, naphtha or a similar solvent may be used to wash off excess oil present and thus promote better adherence of the surfactant to the metallic surfaces of the tool.

A variety of different surface active agents are suitable for purposes of the invention. These may be anionic, cationic or nonionic compounds. In general, the agents found most effective are those marketed for use as water-wetting agents, oil in-water emulsifiers, and water-in-oil demulsifiers. Typical agents which are generally effective include the alkyl phenyl polyethoxyethanols, the alkali metal salts of allyl esters of sulfosuccinic acid, the alkali metal salts of alkylaryl benzene sulfonic acids, the polyethylene oxide ethers of alkyl esters of aliphatic dicarboxylic acids, the soluble salts of alkyl naphthalene sulfonic acids, the alkyl esters of polyalkylene glycols, the polyalkylene esters of fatty acids, the long chain amine hydrochlorides, the long chain polyamides, and the like. Particularly effective agents include polyoxyethylene glycol ethers of dialkyldicarboxylic acids such as the polyoxyethylene glycol ethers of diethyl maleate containing about 6.5 ethylene oxide groups per molecule and mixtures of alkali metal salts of sulfosuccinic acid with alkyl phenyl polyoxyethanols such as mixtures containing about 6 parts of sodium diethylsulfosuccinate, about 3 parts of sodium diethylsulfosuccinate, and about 1 part of isoctyl phenyl polyoxyethanol containing from 9 to 10 ethylene oxide groups per molecule.

The surface active agents employed for purposes of the invention are available as liquids of various concentrations and as pastes or solids. The use of viscous, highly adherent liquid surfactants or pastes is generally preferred but aqueous surfactant solutions having concentrations in excess of about 50% by weight may be advantageous in certain cases. The pastes are particularly effective in deep wells where a relatively thick coating of the surfactant which will persist for a prolonged period is desired. Where a paste or highly concentrated liquid surfactant is used, it is sometimes advantageous to wet the tool with water after the surfactant has been applied and before the tool is introduced into the heavy oil. This provides an initial film of water to facilitate movement of the tool through the heavy oil. A reservoir at the lower end of the tool for providing small amounts of additional water as the tool is lowered may also be advantageous in deep wells where the heavy oil is essentially free of dispersed water.

After the surface active agent has been applied to the surface of the wireline tool, the tool is lowered in the heavy oil in the wellbore. Dispersed water present in the

oil tends to accumulate on the surface of the surfactant coating and thus forms a water film between the oil and the tool. If water was used to wet the surfactant-coated tool before it was introduced into the oil, the dispersed water tends to augment the existing film. This film of water isolates the tool surface from the heavy oil and produces a substantial drop in hydraulic friction as the device is lowered through the column of oil. This in turn results in an increase in the rate at which the tool descends through the oil. Sinker bars can be used in the conventional manner to obtain a further increase if desired. Once the tool has reached the desired level and the contemplated operation has been carried out, it can be withdrawn by means of the wireline without difficulty. The advantages of the method of the invention are exemplified by the results obtained in gas lift wells containing a heavy crude oil with a 14.2° API gravity. Earlier efforts to change the gas lift valves in these wells by wireline operations had not been successful. The rate at which the wireline apparatus moved downwardly through the heavy oil was so slow that such operations were not feasible. It was found that smearing of the tool with about a half pint of a viscous surface active agent containing as the active ingredient a polyethylene glycol ether of dioctyl maleate having about 6.5 ethylene oxide groups per molecule before it was introduced into the well resulted in rapid movement of the tool downwardly through the heavy oil. This use of a surface active agent permitted the routine changeout of gas lift valves in these wells without difficulty. The necessity for pulling the tubing strings from the wells was avoided and substantial savings in both time and money were realized.

What is claimed is:

1. A method for increasing the rate of descent of a wireline tool in a well containing a heavy oil which comprises coating the surface of said tool with a surface active agent capable of promoting the formation of a film of water on the tool and thereafter lowering said tool in said well.

2. A method as defined by claim 1 wherein said surface active agent comprises an alkyl phenyl polyethoxethanol.

3. A method as defined by claim 1 wherein said surface

30

35

40

active agent comprises a polyoxyethylene glycol ether of a dialkyl carboxylic acid.

4. A method as defined by claim 1 wherein said surface active agent is applied to the surface of said tool as a paste.

5. A method as defined by claim 1 wherein water is applied to said tool after said surface is coated with said surface active agent.

6. A method as defined by claim 1 wherein said surface active agent is a viscous liquid.

7. A method as defined by claim 1 wherein said surface active agent is a polyethylene glycol ether of dioctyl maleate containing about 6.5 ethyleneoxide groups per molecule.

15 8. A method as defined by claim 1 wherein said surface active agent is a mixture of about 6 parts of sodium dioctylsulfosuccinate, about 3 parts of sodium dihexylsulfosuccinate, and about 1 part of isooctyl phenyl polyethoxethanol containing from 9 to 10 ethylene oxide groups per molecule.

9. A method as defined by claim 1 wherein said wireline tool is lowered into said well through a lubricator and said surface active agent is applied to said tool in the lubricator.

25 10. A method as defined by claim 1 wherein said surface active agent comprises an alkali metal salt of an alkyl ester of sulfosuccinate acid.
